UNITED STATES PATENT OFFICE.

JOHN H. PEASE, OF CEDAR RAPIDS, IOWA.

FASTENER FOR STORM-WINDOWS.

SPECIFICATION forming part of Letters Patent No. 645,489, dated March 13, 1900.

Application filed October 30, 1899. Serial No. 735,298. (No model.)

To all whom it may concern:

Be it known that I, JOHN H. PEASE, a citizen of the United States, and a resident of Cedar Rapids, county of Linn, and State of Iowa, have invented certain new and useful Improvements in Fastenings for Storm-Windows, &c., of which the following is a specification, reference being had therein to the accompanying drawings, in which—

10 Figure 1 is a vertical section through a window-frame and storm-sash provided with my invention; Fig. 2, a perspective view of the fastening devices and the adjacent parts of the window-casing and storm-sash, showing

15 the sash swung open; Fig. 3, a plan view of the fastening devices as they appear when the sash is closed; the sash being shown in section; Fig. 4, a vertical sectional view on the line 5 5 of Fig. 3, and Fig. 5 a detail vertical section showing the manner of locking the free end of the hook to the bracket on the window-sill.

This invention is designed to provide simple and inexpensive devices whereby a storm-window may be attached to all kinds of window-frames in common use; and it consists of certain novel features of construction hereinafter described, and particularly pointed out in the claims appended.

30 The storm-sash *a* is adapted to fit snugly within the outer edge of the window-frame *b*, bearing against suitable shoulders or beads *c* thereon, the outer face of the sash when the same is closed being flush with the outer face 35 of the window-frame. The sash is detachably hinged to the frame at its upper end by suitable hinges composed of separable plates *d* and *e*.

To lock but at the same time provide for 40 a limited outward movement or adjustment of the lower end of the sash, devices are employed which consist, essentially, of a hooked rod *i*, pivoted to the sash, and a bracket or catch *j*, secured on the sill of the window-frame. The hook *i* is pivotally attached to the sash by a screw-eye *k*, and its hooked free end works through a closed eye or arch *l*, formed on and rising vertically from the outer edge of the base-plate *m* of the bracket. 45 Formed integral with the base-plate *m* and running from a point at one side of the loop or arch *l*, parallel to the inner edge of the

base-plate, to the opposite side of the arch and then forward, where it connects with the arch, is a flange *n*, whose upper edge is below the 55 lower edge of the highest part of the arch. The base-plate is recessed at *o* between the ends of the arch, the recess running back to the wall or flange *n*. The base-plate is also slotted at points beyond the arch, as at *p*, 60 and fastening-screws *q* pass through these slots, the slots running transversely of the plate and being open, so that the bracket may be readily attached to and detached from the sill and be adjusted close up to the inner 65 face of the lower rail of the sash.

In attaching the sash it is first swung on its hinges. Then the end of the hook carrying the screw *i* is inserted through the loop *l* and screwed into the lower rail of the sash. Then 70 the bracket is fastened to the window-sill at the proper point. It will be observed that in attaching the hook to the sash it is necessary that the eye be adjusted vertically, so that the hooked end of the hook will engage over 75 the flange *n* when the sash is swung out, this engagement with the flange serving to lock the hook to the bracket, and thereby hold the sash outward. When it is desired to swing the sash in and lock it, it is simply necessary 80 to lift the hook off flange *n*, let the sash swing inward to place, in which position the eye *k* will project into the arch or loop *l*, and then swing the hook over toward one side and permit it to lie between the flange and the arch, 85 thereby effectually locking the sash in its closed position. It will be observed that the depending end of the hook is longer than the distance between the main body of the hook and the under side of the arch, so that it will 90 be impossible to detach the hook from the bracket, but at the same time the hook may be elevated sufficiently to permit it to slide back over the upper edge of wall or flange *n* when the sash is closing. Thus the hook has 95 a sliding connection with the catch or bracket, but it cannot be detached entirely therefrom after the screw-eye is fastened to the sash. It will be obvious, of course, that in assembling the parts the screw-eye *k* may be secured to the sash before the sash is swung; but in all cases it is essential that the end of the hook carrying the screw-eye be passed through the loop *l* before it is attached to the 100

sash. It is essential that the hook have a vertically-swinging movement in order that it may be engaged over and disengaged from the flange and also that it may have a sidewise pivotal movement in order that it may fold down between the sash and the arch when the sash is locked closed.

It will be observed that this invention is adapted also for fly-screens and awning-shutters, and I therefore do not wish to be confined in respect of the application or use of the invention. It will also be noted that the catch on the window-sill keeps the sliding hook from contacting with and thereby mar-
15 ring the window-sill.

Having thus fully described my invention, what I claim, and desire to secure by Letters Patent, is—

1. A fastening for storm-sash, &c., comprising a hook and means for pivotally connecting it to a sash, so that it may swing vertically and sidewise, and a bracket adapted to be secured to the window-frame and provided with an arch and a flange beyond the
20 arch, said flange and arch being separated, so that the hook may be locked to the flange in its extended position and may lie between the flange and arch in its folded position, whereby the sash may be locked in its open
25 position or in its closed position.

2. A fastening for storm-sash, &c., comprising a hook adapted to be pivotally connected to a sash, and a catch adapted to be
30

removably secured to a window-frame and provided with a closed loop through which 35 said hook works and a flange or projection beyond the loop and terminating below the highest point thereof.

3. A fastening for storm-sash, &c., comprising a hook adapted to be attached to a 40 sash, and a catch adapted to be fastened to a window-frame and provided with an upright arch or loop and a flange beyond the loop or arch, this flange terminating below the loop or arch and extending beyond one side of 45 the same, the free end of the hook working through the loop and on the flange.

4. A fastening for storm-sash, &c., comprising a hook and means for pivotally connecting it to a sash, and a bracket adapted 50 to be attached to a window-frame and provided with an upright arch and an upright flange beyond the arch, said flange being separated from the arch and having one end projecting beyond one side of the arch and the other end connected to the other side of the arch, substantially as and for the purposes set forth.

In testimony whereof I hereunto affix my signature, in the presence of two witnesses, 60 this 26th day of October, 1899.

JOHN H. PEASE.
